UNITED STATES PATENT OFFICE.

VICTOR D. JOHNSON, OF AURORA, ILLINOIS, ASSIGNOR TO FREDERICK C. AUSTIN, OF CHICAGO, ILLINOIS.

WHEELED DUMPING-SCRAPER.

SPECIFICATION forming part of Letters Patent No. 714,706, dated December 2, 1902.

Application filed November 18, 1901. Serial No. 82,733. (No model.)

To all whom it may concern:

Be it known that I, VICTOR D. JOHNSON, a citizen of the United States, residing at Aurora, in the county of Kane and State of Illinois, 5 have invented a certain new and useful Improvement in Wheeled Dumping-Scrapers, of which the following is a specification.

My invention relates to wheeled dumping-scrapers constructed with a bowl or scoop-body suspended from a crank-axle and provided with a bail, which is raised to permit the scoop-body to assume a working position and depressed to raise the scoop-body into position for carrying the load.

15 The objects of my invention are to facilitate the raising of the scoop-body from a working to a carrying position, to permit the draft employed for drawing the scraper to more easily dump the scoop-body and to thereby 20 lessen the power employed for dumping, and to provide certain novel and improved matters of detail and arrangement serving to increase the general efficiency of wheeled dumping-scrapers.

25 In the accompanying drawings, Figure 1 is a top plan view of a wheeled dumping-scraper embodying the principles of my invention. Fig. 2 is a side elevation thereof with the scoop-body in carrying position. Fig. 3 is a 30 section taken through Fig. 2 on line $x-x$. Fig. 4 is an enlarged detail showing one of the slotted standards. Fig. 5 shows a portion of the crank-axle and part of one of the longitudinally-arranged lever-bars secured thereto. Fig. 6 shows the wheeled dumping-scraper with the scoop-body in working position. Fig. 7 is a like view showing the scoop-body in dumping position.

35 A indicates the scoop-shaped body, and B B are the two supporting-wheels. The body A is suspended from a crank-axle C, Figs. 1 and 3, comprising end portions 1, adapted to provide spindles for the wheels, crank-arms 2, which are lateral to an axis passing through the 40 spindles, and a middle high portion 3, which lies transversely over the body when the latter is in either a carrying or a working position. Practically the spindles and crank-arms constitute the two parts of a crank-axle 45 and the high or middle portion 3 a connection between said two parts, it being understood

that as a matter of course the crank action could be utilized by suspending the body from the crank-arms or from the middle or high crank portion 3, which forms a rigid connection between the outer ends of such arms. In the machine illustrated the suspension of the body from the crank-axle considered as an entirety is attained by lever-bars D, conveniently secured to the crank-arms 2 and 60 each arranged to form a double-armed lever, with its two arms projecting respectively forwardly and rearwardly from the crank-axle. The forwardly-extending arms 4 of these levers are pivotally connected with 65 standards E, which are secured to opposite sides of the body at points forward of its middle—that is to say, forward of a transverse line which is intermediate of the front and rear ends of the body. The rear arms 5 of 70 these lever-bars D are connected by links F with a swinging yoke or bail G, which is hinged to opposite sides of the body at points in rear of the middle of the latter. The side arms 6 of this yoke or bail could be pivoted directly to the body, or, as a preferred arrangement, they can be hinged or pivoted to short standards 7, rigidly secured to the body and made somewhat less in height than the forward standards E. When the 75 body is in carrying position, as in Fig. 2, the lever-bars D will be horizontal or approximately horizontal and can be locked in such position by a locking device, such as a pivoted latch 8 on the bail engaging under a 80 catch 9 on the rear side of the body. Under such conditions the forward and rear standards E and 7 will respectively occupy planes 85 forwardly and rearwardly of an axis passing through the spindles, and the yoke or bail, 90 having, as usual, a rearwardly-extending arm 10, will extend rearwardly from its connection with the body and occupy a substantially horizontal position. At such time also the links F, which connect the rear arms of the 95 lever-bars D with the bail-arms at points back of the connections between the bail-arms and the body, will occupy inclined positions, being inclined upwardly and forwardly from their connections with the bail.

100 In order to lower the body into working position, the latch is freed from the body, where-

upon the weight of the latter will cause the body to drop and the bail to swing into an upwardly-inclined position, as illustrated in Fig. 6.

- 5 In order to maintain the body at a proper angle for scooping up the earth, the hounds or swinging draft-frame to which the pole 11 is secured has its opposite side bars 12 provided with swinging draft or stay attachments 10 H, pivoted to the draft attachment at points forward of the pivotal connection between the latter and the body and having hook-shaped lower ends adapted to engage or interlock with catches 13 on opposite sides of 15 the forward end portion of the body. These stay attachments H are connected by links 14 with the ends of the forwardly-projecting arms 4 of the lever-bars D, a desirable arrangement being to provide sliding connections between the lever-bars D and the links 20 14, such as slots 15 in the links and bolts or pins 16 extending through such slots and engaging the lever-bars. By such arrangement the lowering of the bowl and the forward tilt 25 of the lever-bars, as in Fig. 6, will permit the hook-shaped stay attachments to swing downwardly and engage the catches 13, and thereupon the draft will also be exerted upon the lower forward portion of the bowl or body. 30 When the body is thus brought into working position, the crank portion of the axle will lie in a plane which inclines upwardly and forwardly from an axis passing through the spindles, and the lever-bail and the lever-bars 35 will lie in planes which are reversely inclined with relation to the plane occupied by the crank-axle, the lever-bars, however, being desirably at or substantially at right angles to the crank-arms 2. After the body has received a suitable quantity of soil it can be 40 again brought into carrying position by swinging the bail rearwardly and downwardly, the result of such action on the part of the bail being that the lever-bars will tilt from an inclined to a horizontal or substantially horizontal position, and in so doing they will cause the stay attachments H to swing upwardly and out of engagement with the catches 13. When the bail is thus depressed 45 50 for the purpose of breaking the forward cutting edge of the body away from the ground and raising the loaded body into carrying position, the raising mechanism herein provided will operate as a compound lever and 55 involve an extended leverage so arranged as to permit a single operator to raise the loaded body quickly and with comparative ease, and thereby not only lessen the labor, but also permit the body to be heavily loaded 60 before raising it from the ground. Thus when the bail is depressed for the purpose of raising the bowl the crank-arms on the spindles will swing rearwardly about an axis passing through such spindles and simultaneously therewith the bail will be swung downwardly. 65 During such action the pivotal points of connection between the links F and the sides or

arms 6 of the bail will have an extent of movement considerably greater than the greatest extent of movement on the part of the crank portion of the axle, and, if desired, said points of connection between the lever-bars, links F, and the bail can be made to traverse double the distance traversed by the tilting or swinging crank portion of the axle. This relative 70 difference between the movement of the crank portion of the axle or the crank-arms and the points of connection between the lever-bars D and the bail can be determined and varied by the extent to which the rear arms 5 of the 75 lever-bars extend back from the crank-axle, the extent to which the points of connection between the links F and the arms 5 are set back from the crank-arms, and the extent to which the points of connection between the 80 links F and the bail are set back and away from the points of connection between the bail and the body. The arrangement described provides a compact and exceedingly powerful mechanism for raising the loaded body without, however, necessitating any unusual or undesirable extent of movement on the part of the crank-axle and the bail and without incurring any unusual or undesirable extent of movement on the part of the bowl 85 or body. The swinging bail also has its middle portion connected with the middle portion of the high part 3 of the crank-axle by a link connection 17, Figs. 1 and 3, such link connection being preferably attached at one end 90 to a short arm 18 on the bail and to an arm 19, which is secured upon such high part of the crank-axle. This connection between the bail and the axle when employed is adapted 95 to have an extent of movement corresponding 100 with the extent of movement on the part of the connections between the lever-bars D and the bail, and thereby it may be used as auxiliary to said connections between the bail 105 and lever-bars D. 110

In order to dump the load, the operator will lift the rear end of the body by taking hold of its rearwardly-projecting handles 20, and thereby permit the forward end of the body to tilt down and engage the ground, while 115 the bail is locked to the body by the catch 8. When the body is in position for dumping, substantially as in Fig. 7, a long latch I on the pole or draft frame will engage catch 9 on the body, and thereby prevent the body 120 from tilting back until such catch I has been released from the body. In order to facilitate this dumping action on the part of the body and permit the forward draft to readily effect the same, the hounds or sides 12 of the 125 draft attachment have sliding pivotal connections with the standards E, which are secured to and arranged to rise from opposite sides of the body at points forward of the middle of the latter. By such construction 130 the draft attachment has free rear end portions formed by the bars or hounds 12, connected with upright guides on the scoop-body by shifting pivotal connections which auto-

5 matically shift when the scoop-body is tilted, it being understood that these rear end portions of the draft attachment are not attached to the axle and are free from both the axle and the scoop-body, with the exception, of course, that they are indirectly connected with the scoop-body by means of the guides and automatically-shifting pivotal connections. In the arrangement shown these up- 10 rights or standards have vertical slots 20 (see also Fig. 4) for pins or rolls 21 on the sides 12 of the draft attachment. When the body is in either a carrying or working position, these rolls will be at the lower ends of the 15 vertical guideways afforded by the slotted uprights or the body. When, however, the body is tilted for the purpose of dumping the load, these shifting pivotal connections between the draft attachment and the body 20 shift upwardly along the guideways and in so doing shift upwardly from a horizontal plane passing longitudinally and centrally through the body, whereby the draft upon the body in a direction to tilt the same will 25 practically shift toward the outer end of lever-arms secured to the body. This arrangement lessens the work of dumping and renders it an easier matter for the team to cause the body to tilt to an extent to completely dump the load.

In order to limit the extent of tilt or swing on the part of the body in dumping, I can provide any suitably-arranged stop device. For example, the uprights or standards E can 35 have stops 22, which engage upon the sides of the draft attachment when the body is in dumping position, as in Fig. 7, or such stops may be provided upon the draft attachment and arranged to engage the standards K.

40 When the body is in carrying or working position, the guideways for the shifting pivotal connections between the draft attachment and the body are on vertical or substantially vertical lines forward of an axis 45 passing through the spindles, and an axis passing through these oppositely-arranged shifting pivotal connections between the draft attachment and the body will be on a plane below an axis passing through the spindles.

50 With reference to certain minor details shown the links F are double links, and the standards E and 7 are each preferably composed of a couple of parts respectively secured to an inner and outer side wall of the screw-body, it being observed, however, that this is a common way of forming links and standards in wheeled dumping-scrappers of the 55 class to which my invention relates.

What I claim as my invention is—

60 1. A wheeled dumping-scraper comprising a crank-axle; a scoop-body; lever-arms rigid with and extending forwardly and rearwardly from the crank portion of the axle; a bail pivotally connected with the scoop-body; link 65 connections between the bail and the rearwardly-extending lever-arms; and link con-

nctions between the forwardly-extending lever-arms and the scoop-body.

2. A wheeled dumping-scraper comprising a crank-axle; lever-bars rigid with the crank- 70 arms and extending forwardly and rearwardly therefrom; a bail pivotally connected with the scoop-body; link connections between the rearwardly-extending portions of the lever-bars and the bail, and link connections between the forwardly-extending portions of the lever-bars and the scoop-body. 75

3. A wheeled dumping-scraper comprising an axle having spindles for the wheels and a crank portion consisting of crank-arms lateral to the spindles and connected together; lever-bars secured to the crank portion of the axle and providing lever-arms extending forwardly and rearwardly therefrom; a bail having its sides pivotally connected with the 80 scoop-body in rear of the spindles; links connecting the sides of the bail with the rearwardly-extending lever-arms; and standards secured to the sides of the scoop-body at points forward of the axle-spindles; the forwardly-extending lever-arms being pivotally connected with said standards. 85

4. In a wheeled dumping-scraper, a crank-axle; a tilting scoop-body suspended from the crank-axle and provided with upright side 95 guides; and a draft attachment having free rear end portions connected with the upright guides on the scoop-body by automatically-shifting pivotal connections.

5. In a wheeled dumping-scraper, a crank- 100 axle and a tilting scoop-body supported thereby; arms secured to the crank-axle and extending forwardly therefrom; upright side guides rigid with the scoop-body and pivotally connected with said forwardly-projecting 105 arms on the crank-axle; and a draft attachment having shifting connections with the upright guides, said connections permitting the scoop-body and the draft attachment to tilt independently the one of the other. 110

6. A wheeled dumping-scraper comprising a crank-axle; a scoop-body suspended from the crank-axle; a draft attachment; slotted standards rigid with and rising from the scoop-body; and shifting pivotal connections 115 between the draft attachment and the slotted standards.

7. A wheeled dumping-scraper comprising a crank-axle; a scoop-body; lever-arms projecting forwardly and rearwardly from the 120 crank-axle; a bail hinged to the scoop-body; connections between the rearwardly-projecting lever-arms and the bail; a locking device for locking the bail to the scoop-body; a draft attachment; standards secured to and rising 125 from the scoop-body; shifting pivotal connections between the draft attachment and the standards; and pivotal connections between said standards and the forwardly-projecting lever-arms. 130

8. A wheeled dumping-scraper comprising a scoop-body; a crank-axle; a bail pivotally

connected with the scoop-body; bars D, secured to the crank-axle and extending forwardly and rearwardly therefrom; link connections between the rear end portions of the bars D and the bail; slotted standards secured to the scoop-body; and a shaft attachment having shifting pivotal connections with the standards D.

9. A wheeled dumping-scraper comprising
a scoop-body; a crank-axle from which the
scoop-body is suspended; lever-arms projecting
forwardly from the crank-axle; standards

rising from the scoop-body; pivotal connections between said lever-arms and the standards; a draft attachment having shifting pivotal connections with the standards; and stops arranged to effect an engagement between the lever-arms and draft attachment when the scoop-body is in dumping position. 15
